LAMP BASE

Frank E. Luby, 344 Mason Court,
Sycamore, Ill. 60178

Filed Mar. 5, 1969, Ser. No. 16,037

Term of patent 14 years

Int. Cl. D26—02

U.S. Cl. D48—20

Fig. 2.

Fig. 3.

Fig. 1.

Fig. 4.

FIG. 1 is a perspective view of my new design embodied in a decorative lamp base;

FIG. 2 is a front view thereof, on an enlarged scale;

FIG. 3 is a side view thereof, on an enlarged scale;

FIG. 4 is a top plan view thereof, on an enlarged scale;

FIG. 5 is a perspective view of my new design embodied in a combined decorative lamp base and clock;

FIG. 6 is a front view thereof, on an enlarged scale;

FIG. 7 is a side view thereof, on an enlarged scale; and

FIG. 8 is a top plan view thereof, on an enlarged scale;

The bottom of the lamp base is substantially plain and unornamented.

I claim:

The ornamental design for a lamp base, substantially as shown and described.
